UNITED STATES PATENT OFFICE.

JOSEPH ULMSTEAD FRY, OF GRENOVA, KANSAS, ASSIGNOR OF ONE-HALF TO
JAMES L. HART, OF SAME PLACE.

CORN-HARVESTER.

SPECIFICATION forming part of Letters Patent No. 660,768, dated October 30, 1900.

Application filed February 12, 1896. Serial No. 579,039. (No model)

To all whom it may concern:

Be it known that I, JOSEPH ULMSTEAD FRY, a citizen of the United States, residing at Grenola, in the county of Elk and State of 5 Kansas, have invented certain new and useful Improvements in Corn-Harvesters; and I do hereby declare the following to be a full, clear, and exact description of the invention, such as will enable others skilled in the art to 10 which it appertains to make and use the same.

The invention relates to certain new and useful improvements in corn harvesters or gatherers; and it has for its object to provide a simple and cheap attachment which may 15 be readily applied to the side of an ordinary farm-wagon and by which standing corn may be gathered and cut, one row at a time, and delivered or conveyed into the wagon-box as the team draws the wagon along beside a row 20 of standing corn. The attendant sits in the wagon near the machine.

The invention consists in the construction and novel combination of parts, as hereinafter fully described and claimed.

25 In the drawings annexed to and forming part of this specification, Figure 1 is a side elevation of my improvement. Fig. 2 is a vertical cross-section. Fig. 3 is a detail view of the elevating-belts. Fig. 4 is a detail view 30 of the supporting-frame. Fig. 5 is a detail perspective view of the cutter; and Fig. 6 is a detail perspective view of the fender, the cutter, and the guard-arms.

Like characters of reference indicate like 35 parts in the various views.

Referring now to the details of the drawings by letter, A designates the side of a farm-wagon of known construction.

B represents the supporting-frame of my 40 improved device, provided with hooks b near the upper ends of its side bars, adapted to be engaged over the top edge of the side of the wagon-body, as shown in Fig. 2, and when thus in place the side-board A' is put in place 45 and rests upon the hooks b, the said side-board being provided with the depending springs A², adapted to embrace the side of the wagon-body. The hooks b may also be engaged over the top of said side-board if nec- 50 essary.

The supporting-frame B has at the bottom

a thumb-screw or its equivalent X, that engages against the bottom of the wagon-box. This supporting-frame B has its end bars arranged obliquely, as shown, and they are slotted, as shown at a, in which slots extend the lugs or projections or analogous means a' on the likewise obliquely-disposed bars C of the sliding frame, which are adapted to be raised and lowered by the lever C', pivotally mounted at c' on the longitudinal bar R of the stationary frame and connected by the link C² with the transverse connecting-bar C³ of said sliding frame, so that by manipulation of the lever C' the sliding frame may be raised or 60 lowered in the oblique plane, and when desired to hold the same in either of its adjusted positions the end of the lever may be engaged under the knob c⁴ or c⁵ on the front inclined bar of the stationary frame. This adjustment in an oblique direction is so as not to disturb or interfere with the tension of the chain which imparts motion to the elevating-belts L. 70

E is a supporting platform or plate mounted upon the sliding frame in any suitable manner. This platform or plate E at its outer and lower end is supported by the inclined brace-arm D², detachably and pivotally connected at its lower end with the sliding frame 80 and likewise at the upper end with the said plate E, near the lower end of the latter, as shown in Fig. 2. This plate or platform E may be further braced by the brace-arms d, as shown in Fig. 1. 85

F is a concave fender secured to the rear edge of the plate or platform E and extending a sufficient height above the knife G to have the desired effect. The free end of this fender constitutes a guard. In front of the 90 knife G extend guard-arms f f'. These guard-arms serve to conduct the corn or other material, which is received and embraced between them as the team moves the wagon forward, into and against the knife or cutter G, 95 which is substantially crescent-shaped, as shown, and is secured to the lower end of the plate or platform and has its back bearing against the inner face of the concave fender F. 100

Mounted on the plate E is the block H, which is stepped, as shown at h, and mounted

in these steps are the inclined shafts K, having their bearings in the plates E and 2, 2 and 3, 3 and 4, 4 and E, respectively, the longer shaft K being near the upper ends of the plates E and 2 and above the block H, while the lower set of shafts K have their bearings in the plates 2, 3, 4, and E at the stepped lower end of said block H, the plate 2 resting on the inclined upper face of said block H 5 and the plates 3 4 resting on the stepped lower end of said inclined block H and projecting sufficiently far over upon their faces to form the bearings for the pulleys P and P'. The shaft K of the lowermost pulley P² has its bearing in the plates 4 and E, near the lower end of the latter, and is provided at its lower end with the sprocket-pulley M for the reception of the sprocket drive-chain N. The drive-chain N is connected with a sprocket-wheel 20 N' on the extreme outer end of the hub of the rear wheel of the wagon, on the same side thereof to which the block H, &c., is attached. Belts L, provided with suitable teeth or projections I, connect the stepped pulley K' 25 with the pulleys P P' P². These belts L are arranged in planes of different elevations. The lower pulleys around which the belts L pass are made larger as the series progresses upward, the lower pulleys being the smallest, 30 the next ones somewhat larger, and the next still larger, so that the lowermost belt will move the slowest, the next a little faster, and the uppermost one still faster, and thus on, using as few or as many belts as may be desired. 35

In practice as the team moves forward the corn is gathered in by the guard-arms f f' and brought against the knife or cutter G, and as the material is cut the heads of corn 40 fall into the recess or elevating-trough, where said cut corn is caught by the fingers of the belt and carried into the wagon, and as the uppermost belt moves faster than the lower-

most belt the cut corn will be moved from the cutter, so as to prevent it from falling back 45 thereon and choking the machine.

Modifications in detail may be made without departing from the spirit of the invention or sacrificing any of its advantages.

Having thus fully described my invention, 50 what I claim, and desire to secure by Letters Patent, is—

In a corn-harvester of the class described, the combination with a vertical supporting-frame provided with hooks for engaging the top edge of a wagon-box; a sliding frame connected with said supporting-frame; an inclined platform connected near its upper end with the upper end of said sliding frame and connected near its lower end with said sliding frame by an inclined removable brace-rod; a hand-lever connected with said sliding frame for raising, lowering or maintaining it in its adjusted positions; a stepped block mounted on said inclined platform, movable upward and rearward and downward and forward in a vertical plane with said sliding frame and platform and provided with upper and lower sets of different-sized pulleys; toothed belts mounted on said pulleys; a concave fender mounted on the inclined platform and provided with a cutter and guard-fingers; and a sprocket-chain belt, connecting a sprocket-pulley on said lower set of different-sized pulleys with a sprocket-wheel on the extreme outer end of the hub of one of the rear wheels of the wagon, substantially as set forth.

In testimony whereof I have signed this specification in the presence of two subscr- 80 ing witnesses.

JOSEPH ULMSTEAD FRY.
